H. SWARTZ

COAL GAS CARBURETOR

Filed Feb. 3, 1921

FIG. I.

FIG. II.

FIG. IV.

INVENTOR:

HENRY SWARTZ,

*by Arthur C. Baugh,
Attorney.*

Patented Mar. 6, 1923.

1,447,737

UNITED STATES PATENT OFFICE.

HENRY SWARTZ, OF PHILADELPHIA, PENNSYLVANIA.

COAL-GAS CARBURETOR.

Application filed February 3, 1921. Serial No. 442,218.

To all whom it may concern:

Be it known that I, HENRY SWARTZ, a citizen of the United States, residing at Philadelphia, in the county of Philadelphia and 5 State of Pennsylvania, have invented a certain new and useful Improvement in Coal-Gas Carburetors, whereof the following is a specification, reference being had to the accompanying drawing.

10 My invention relates to devices designed to mix atmospheric air with the gaseous primary products of combustion from a coal fire to facilitate the complete combustion of such products and consequent economy of fuel.

The form of my invention hereinafter described is adapted as an accessory attachment for an ordinary house heating furnace. However, it is to be understood that 20 it may be employed in conjunction with any type of furnace.

As hereinafter described; my improved device includes a tubular air conduit having means to rigidly secure it in an opening 25 extending through the door or wall of a furnace; said conduit carrying, at its inner end, a mixing chamber with air inlets and outlets and having, at its outer end, means adapted to afford a permanent air 30 inlet port of predetermined size and valvular means whereby additional air inlet ports may be opened and closed.

My invention includes the various novel features of construction and arrangement 35 hereinafter more definitely specified. However, the specific details of construction and arrangement of the air inlet valvular means aforesaid are claimed in my copending application Serial No. 523,152 40 filed December 17, 1921, for Letters Patent of the United States.

In said drawing; Fig. I is a plan view of a carburetor embodying my invention.

Fig. II is an outer end elevation of said 45 carburetor.

Fig. III is a vertical sectional view of said carburetor taken on the line III, III in Fig. I.

Fig. IV is a transverse vertical sectional 50 view of the mixing chamber shown in Figs. I and III, taken on the line IV, IV in Fig. III.

In said figures; 1 is a tubular air conduit (conveniently formed of a piece of one-quarter inch gas pipe) fitted through the 55 opening 2 in the door or wall 3 of a furnace

inclosure, and carrying, at its inner end, the mixing chamber 5, which is rigidly connected with said conduit 1 by the screw thread 6 and jam nut 7. Said chamber 5 60 is conveniently formed of a single casting of iron alloyed with silicon and manganese in such proportions as to resist oxidation. Said chamber 5 overhangs the fire 8 as indicated in Fig. III, so as to come within 65 the primary gaseous products of combustion 9 arising from said fire. Said chamber 5 has, at its bottom, a series of nozzles 10, which, as shown in Fig. IV, have respective cylindrical vents 11 outwardly 70 flared at their outer ends. Said chamber 5 also has a series of vents 14 at its inner edge and a series of vents 15 extending obliquely upward with respect to said vents 11 and 14. I also find it convenient to provide said 75 chamber 5 with the baffle plate or rib 17 extending transversely in opposition to the inner end of the air inlet conduit 1 so as to distribute the incoming air throughout said chamber 5. 80

It is to be understood that the heat of the fire 8 causes circulation of air through said vents 11, 14 and 15, inducing the flow of air inwardly through said conduit 1. I prefer to provide said conduit with the inlet 85 port 19, (conveniently formed by drilling said conduit 1) so as to draw back into the furnace any unconsumed gaseous products from said fire 8 which otherwise might tend to escape at the crevices around the door 3, 90 and return the same through the vents aforesaid. However, I provide for a continuous supply of fresh air from the outer atmosphere, as follows:

I provide the outer end of said conduit 95 1 with the valve casing 21 which is engaged therewith by the screw thread 22; said conduit 1 and casing 21 being rigidly connected with said door or wall 3 by the jam nut 23. Said casing 21 is conveniently formed 100 of cast metal having the cross bar 25 with the central bearing 26 in coaxial relation with said conduit 1, to receive the tubular axial boss 27 of the rotary cap valve 28 which is conveniently provided with the 105 washer 29 and riveted so as to be permanently pivotally connected in said valve casing, as best shown in Fig. III. Said valve 28 is provided with a permanent air inlet port 30 of such size as is predetermined 110 to be best suited for the type of furnace in connection with which the carburetor is

used, and may be simply a hole drilled through said boss 27.

However, I also prefer to provide said valve plate 28 with auxiliary ports 32, as shown in Fig. II, which are closed when said valve is in the position indicated in the drawing but which may be partially or entirely opened by turning said valve upon its axial boss 27, and the lugs 34 are provided to 10 conveniently effect such rotation manually. It may be observed that said ports 32 are of such size that they may be used to check the fire 8 by a supply of air in excess of that required to effect complete combustion 15 of said primary gaseous products 9. Such valvular means enables the operator to pre-determine the air supply, by adjustment of said plate 28 to vary the size of the air inlets in accordance with the velocity of the air 20 induced by the draft of the furnace to which my improved carburetor is attached.

However, it is to be understood that I do not desire to limit myself to the precise details of construction and arrangement 25 herein set forth, as it is obvious that various modifications may be made therein without departing from the essential features of my invention, as defined in the appended claims.

30 I claim:

1. In a coal gas carburetor; the combination with a tubular air conduit having a screw thread at each end thereof; of means arranged to rigidly connect said conduit with 35 an opening in a furnace inclosure, including a jam nut; a mixing chamber at the inner end of said conduit, comprising a single hollow casting of oxygen resisting metal having a screw thread fitted to said 40 conduit; an internal baffle element in opposition to said conduit, a series of projecting nozzles with vents extending from the bottom of said chamber and outwardly flared at their outer ends, a second series of vents 45 above said first series and at the inner edge of said chamber, and a third series of vents above said second series and extending obliquely with reference to said first and second series of vents; and means attached to said 50 screw thread at the outer end of said conduit, arranged to control the admission of air to said conduit.

2. In a coal gas carburetor; the combination with a tubular air conduit having a 55 screw thread at each end thereof; of means

arranged to detachably rigidly connect said conduit with an opening in a furnace inclosure; a mixing chamber at the inner end of said conduit, comprising a casting of oxygen resisting metal having a screw 60 thread fitted to said conduit; an internal baffle element in opposition to said conduit, a series of vents extending through the bottom of said chamber and outwardly flared at their outer ends, a second series of vents 65 above said first series and at the inner edge of said chamber, and a third series of vents above said second series and extending obliquely with reference to said first and second series of vents; and means attached 70 at the outer end of said conduit arranged to control the admission of air to said conduit.

3. In a coal gas carburetor; the combination with a tubular air conduit; of means arranged to rigidly connect said conduit 75 with an opening in a furnace inclosure; a mixing chamber at the inner end of said conduit, comprising a single hollow casting of oxygen resisting metal having a screw thread fitted to said conduit; a series of projecting nozzles with vents extending from the bottom of said chamber, a second series of vents above said first series and at the inner edge of said chamber and a third series of vents above said second series and 80 extending obliquely with reference to said first and second series of vents; and means attached at the outer end of said conduit arranged to control the admission of air to 85 said conduit.

4. In a coal gas carburetor; the combination with a tubular air conduit; of means arranged to rigidly connect said conduit with an opening in a furnace inclosure; a mixing chamber at the inner end of said 90 conduit, comprising a single hollow casting of metal having a screw thread fitted to said conduit; a series of projecting nozzles with vents extending from the bottom of said chamber, and a second series of vents 95 above said series and at the inner edge of said chamber.

In testimony whereof, I have hereunto signed my name at Philadelphia, Pennsylvania, this twenty-seventh day of January, 1921.

HENRY SWARTZ.
